UNITED STATES PATENT OFFICE.

FRANK C. WILLIAMS, OF PHILADELPHIA, PENNSYLVANIA, ASSIGNOR TO THE SAFETY BLOCK SIGNAL COMPANY, A CORPORATION OF DELAWARE.

RAILWAY SIGNAL AND STOPPING MECHANISM.

1,196,196.

Specification of Letters Patent. Patented Aug. 29, 1916.

Application filed August 18, 1911, Serial No. 644,826. Renewed February 18, 1916. Serial No. 79,221.

To all whom it may concern:

Be it known that I, FRANK C. WILLIAMS, a citizen of the United States, and a resident of the city of Philadelphia, in the county of Philadelphia and State of Pennsylvania, have invented certain new and useful Improvements in Railway Signal and Stopping Mechanism, whereof the following is a specification, reference being had to the accompanying drawings.

This invention relates to signal systems wherein the signal mechanism of each block or section is independent of the signal mechanism of the adjoining blocks or sections and is particularly directed to signals which are normally maintained in "safety" position by a normally closed electric circuit, and which are actuated to indicate "danger", by gravity.

The principal objects of this invention are to provide a signal system comprising signal and stopping mechanism which is simple in design, positive in actuation, and in which the main signal members may be economically maintained normally in the "safety" position in opposition to the force of gravity.

Other objects of this invention are to provide stopping mechanism electrically connected with the signal mechanism and arranged to be actuated in accordance therewith, to automatically stop a car or train, and to provide auxiliary stopping mechanism electrically connected to the main stopping mechanism to be actuated in opposition to said signal mechanism and connected stopping mechanism.

Further objects of this invention are to yieldingly mount the stopping members, and to provide means whereby they may be shifted either accidentally or maliciously to an abnormal inoperative position in opposition to the direction of movement to their normal inoperative position, without affecting their respective mechanisms and whereby they are automatically returned to their "danger" position into operative engagement with their actuating mechanism, when released, and to provide means whereby, when one of said stopping members is shifted in any direction from its "danger" position, the other stopping member will be automatically actuated to its operative position to effect the stopping of a car or train.

This invention further includes all of the

various novel features of construction and arrangement hereinafter more definitely specified.

The form of this invention hereinafter described, provides a railway which is divided into blocks or sections with a signal station located near the end of each block, each station comprising a semaphore normally maintained in "safety" position by a detent which is maintained operative by a normally closed electric circuit, including the rails of the track; stopping mechanism having a stopping member operative to engage means carried by a car or train to effect its stopping when in "danger" position, and having electric connections which are arranged to be alternately closed and broken by the actuation of the mechanism at the signal station, to effect the actuation of the mechanism at the stopping station; an auxiliary stopping station having mechanism electrically connected to be actuated by the actuation of the mechanism at the main stopping station which is connected with said main signal station, and operative to actuate its stopping member in opposition to the stopping member of the main stopping station.

In the accompanying drawings, Figure 1 is a fragmentary side elevational view of a locomotive and its tender, comprising stopping mechanism; together with a diagrammatic illustration of the signal and stopping members and the wiring connections between the same; Fig. 2 is a diagrammatic view showing in side elevation the signal and stopping mechanisms and their connections with the rails of the track; Fig. 3 is a fragmentary sectional view of the actuating mechanism taken on the line 3-3 in Fig. 2; Fig. 4 is a fragmentary elevational view of the automatically actuated clutch connection between a motor and the signal actuating mechanism; and Fig. 5 is a fragmentary view of the valve tripping device carried by the locomotive.

Referring to said figures, the locomotive 5 and tender 6 are arranged to traverse the track rails 7 and 8, which are divided into blocks or divisions 9 and 10, by having the adjacent ends of one of the rails of each block separated by insulation 11, as best shown in Fig. 2.

Signal stations 12 are disposed along the track at suitable distances from the ends of

the respective blocks, the signal stations opposite the respective blocks being operative to protect the block ahead, with reference to the direction of the movement of the 5 train.

Each signal station comprises a semaphore 14 which is carried by a shaft 15, journaled in the signal casing 16 and carrying a brush wheel 17, which is in toothed engagement with the pinion 18 on the shaft 19, journaled in the frame 20. Said shaft 19 also carries the gear 21 which is in toothed engagement with the pinion 22 and gear 23.

The pinion 22 is carried by the shaft 24 15 which is journaled in the frame 20 and which also carries the ratchet 25 secured thereto and the gear 26 which is loosely mounted thereon and which carries a pawl or dog 30, pivoted thereon and arranged to engage the teeth of the ratchet 25, as shown in Fig. 2 of the drawing, to prevent a clockwise movement of said ratchet with respect thereto.

The gear 26 is in toothed engagement with 25 the pinion 27 on the shaft 28, which is journaled in the frame 20 and which carries the fly-fan 29 operative to retard the mechanism when shifted by gravitation of the semaphore 14 to the "danger" position as best shown in Fig. 2.

The pinion 27 is of sufficient width to be engaged by the detent 31 on the switch lever 32, which is normally maintained in engagement therewith to prevent its rotation, 35 and consequently, to retain the semaphore 14 in the "safety" position. Said detent 31 is arranged to be shifted out of engagement therewith, by gravity, to permit its rotation, as will be hereinafter more fully described.

40 The switch lever 32 is pivoted at 33 to the contact terminal 34 and is provided with a counterbalance weight 35 at one end, and with a contact finger 37 at the other end, arranged to engage the adjustable contact 38 in the contact terminal 39, when said switch lever 32 is shifted to engage its detent 31, with said pinion 27, by the magnet 40 of which said switch lever 32 is the armature.

45 The gear 23 is carried by the shaft 42, 50 which is journaled in the lateral extension of the frame 20, and which carries the gear 43 in toothed engagement with the pinion 44 on the shaft 45 of the electric motor, 46, comprising an armature 47 and the field 55 coil 48.

Connected in series with the field coil 48 of the motor 46, is a magnet 50, whose armature 51 is pivoted at one end to the motor frame and is engaged at its free end with the centrally pivoted rocking lever 53 having the bifurcated lug 54 projecting upwardly therefrom and embracing one end of the clutch lever 55, which is pivoted centrally upon the pintle 56. The other end of said lever 55 is provided with a yoke 58 which

straddles the slideable clutch block 59, loosely engaged in the circumferential groove 60 therein.

It will be seen that any oscillatory movement of the lever 55 effected by the movement of the armature 51, serves to shift the clutch block 59 longitudinally upon the shaft 42 to engage said clutch block with the clutch member 61, which is secured to the shaft 42. The disengagement of the 75 clutch block 59 is preferably effected by the weight 63 opposite to the end engaged by the armature 51.

It will be obvious from the foregoing description that the motor 46 is connected with 80 the signal mechanism only when said motor is actuated, and such connection is automatically effected by the electrical current, when closed to actuate said motor, and that the actuation of the signal mechanism by said 85 motor in the direction of the arrows indicated thereon at the signal station shown in Fig. 2 is effected independently of the gear 26 and pinion 27 which are locked in stationary relation by the detent 31 on the 90 switch lever 32, during the actuation of said motor and serve to maintain the semaphore in "safety" position until released by a car or train traversing the track, as will be hereinafter more fully described.

95 The main stopping station of each block is disposed closely adjacent to the track and preferably opposite to its respective signal station in the block behind the block protected thereby and at such distance from the 100 block divisions as to effect the stopping of the train before entering the block protected thereby, and its auxiliary stopping station is disposed along the track in the block protected by said signal station near its entrance 105 end.

As the actuating mechanism inclosed within the casing 65 of the stopping station is substantially identical with the actuating mechanism of the signal station, in the casing 110 16, above described, the similar parts thereof will be hereinafter referred to by the same reference numerals as employed in the mechanism at said signal station.

The brush wheel 17 of the main stopping 115 station is provided with a lever 70 having a weight 71 adjustable thereon, and arranged to rotate said brush wheel and the mechanism connected therewith until the lever 70 engages the stop pin 72 in the position 120 shown in Fig. 2 of the drawing.

Mounted on the shaft 15 of the mechanism at the main stopping station, is a bevel gear 74 arranged to mesh with a bevel gear 75 on the shaft 76, which carries the blade 125 77 at the top, and the radially projecting pin 78 at the bottom. Said shaft 76 is journaled at its upper end in the bearing sleeve 79, and at its lower end in the bearing box 80 which has a cylindrical wall provided 130

with a cam groove 82 in which the projecting pin 78 is mounted to ride, and which comprises an upwardly extending oblique portion 83 and a horizontal portion 84 respectively extending from a centrally depressed region 85, said depressed region being cooperative with the pin 78 to retain the blade 77 in operative position, in which position the said pin 78 is in electrical contact with the contact plate 86.

The auxiliary stopping station is disposed adjacent to the track within the block protected by the signal station above described, and comprises the casing 90 inclosing actuating mechanism substantially identical with the mechanism at the main stopping station, and so connected therewith as to be actuated in opposition thereto; that is to say, when the stopping blade 77 at the main stopping station is disposed in its operative position to stop a car or train traversing the track, the corresponding blade 91 at the auxiliary stopping station is disposed in its normally inoperative position, and vice versa.

It may be here stated that any movement of the blade 77 in either direction from its operative position will effect the movement of the blade 91 at the auxiliary stopping station, to a position operative to stop a car or train traversing the track, so as to prevent the movement of a train through said block, unless the signal and stopping mechanism is operative to protect said block.

In each of the stopping stations, and at the signal station, the brush wheel 17 is provided with brush contacts 93 in wiping engagement with the aligned contact plates 94 and 95 which are separated by the insulation 96, and are included in electric circuits hereinafter specifically described.

The magnet 40 of the main signal station is connected by the wires 97 and 98, respectively connected to the track rails 7 and 8, which are electrically charged by the battery 100. As best shown in Fig. 2, said wires 97 and 98 are connected to the rails near the end of the block first entered by the car or train, and the battery 100 is connected to said rails at the opposite end thereof so as to insure the short-circuiting of the magnet 40 so long as a car or train remains in the block to which it is connected.

The contact terminal 34 is connected with the contact plate 94 by the circuit 102 which includes the motor 46, magnet 50 and battery 103 and is completed through a brush contact 93, brush wheel 17, shaft 15, wire 104, contact terminal 39 and the switch lever 32, when the magnet 40 is energized to engage the finger 37 with the contact point 38.

The magnet 40 of the main stopping station is included in the circuit 105 which includes the battery 107 and has its opposite

ends respectively connected to the contact plate 95, and the shaft 15 of the brush wheel 17 at the signal station, so that when the brush contact 93 is engaged with the plate 94, the circuit 105 will be broken, but when 76 said brush contact 93 is engaged with the contact plate 95, the circuit 105 will be completed through the brush wheel 17, and the magnet 40 in the circuit 105, energized to uplift the switch lever 32 of the main stopping station, to its operative position to lock the pinion 27 and to close the local circuit 102 of said main stopping station to energize its motor 46 and thereby actuate the mechanism to shift the blade 77 into its normally inoperative position corresponding to the "safety" position of the semaphore 14.

The magnet 40 of the auxiliary stopping station is included in the circuit 106, which includes the battery 107 and has its opposite 85 ends respectively connected with the contact plate 86 and with the shaft 15 of the brush wheel at the main stopping station, and said circuit is closed through said shaft 15, gears 74 and 75, shaft 76 and pin 78 96 only when the mechanism of the main stopping station is in a position to maintain the blade 77 operative to stop a car or train traversing the track in which position of the blade 77 and the mechanism connected 95 therewith the circuit 106 is closed to effect the actuation of the mechanism at the auxiliary stopping station, and to thereby shift the blade 91 to its inoperative position.

The signal station is provided with contact plates 109, 110, the contact plate 109 being connected by the wire 111 with the electrical contact plate 112 preferably disposed between the track rails in the block adjacent to the entrance end of the block protected 105 by said signal, and the contact plate 110 is connected by the wire 113 with the contact plate 114 preferably disposed between the track rails, and in alinement with the plate 112 in the block protected by said signal, at 110 a suitable distance from its entrance end. A common ground return wire 115 connects the shaft 15 of the signal station with the track rail 8.

The stopping mechanism carried by each 115 locomotive 5 is connected to actuate the throttle lever 120 to shut off the motive power and to contemporaneously actuate the train pipe valve 121 of the train pipe 122 to apply the brakes by releasing the pressure. 120 Said stopping mechanism comprises the cylinder 123, having a piston connected with the actuating lever of the valve 121 and arranged to be actuated by the air pressure from the air brake system.

The cylinder 123 is connected by the pipe 124 with the air pressure reservoir 125 of the air brake system. Said air pressure is admitted to the cylinder 123 through said pipe 124, by a suitable slide valve of any 130

well known construction, operative to admit and exhaust the pressure, to and from said cylinder.

The admission of air through the pipe 124 to the cylinder 123 is automatically controlled by the valve 129 having a weighted lever tending to automatically open said valve when released. Said lever is normally retained in position to maintain the valve 129 closed by the magnet 130 disposed in the circuit 131, including the battery 132, wheels of the tender 133 and the contact roller 134, which latter is disposed in position to engage the respective contact plates 112 and 114 as the locomotive traverses the rails, through the successive blocks.

It will be seen that the battery 132 normally retains the stopping mechanism carried by the locomotive above described in an inoperative position, to permit the movement of said engine, and that when the contact roller 134 engages the contact plate 112 when the semaphore 14 is in the position shown in Fig. 2 of the drawing, the circuit 131 will be short-circuited by the completion of that portion directly engaged with the battery 132 through the plate 112, wire 111, contact plate 109, brush wheel 17, wire 115 and the track 8, which short-circuiting will deenergize the magnet 130 and effect the release of the lever of the valve 129 and permit it to automatically open. If, however, the semaphore is set to the "safety" position, the engagement of the contact roller 134 with the plate 112 will not effect the short-circuiting of the circuit 131. It will be seen that the same short-circuiting effect will be attained when the contact roller 134 engages the contact plate 114, if the semaphore 14 remains in the "safety" position after the car or train enters the block protected thereby.

The stopping mechanism carried by the locomotive may be mechanically actuated independently of the valve 129 in the pipe 124, which is provided with a by-pass connection, including the pipe 140, which is provided with a valve 141 having a weighted controlling lever 142 extending oppositely from its center of oscillation, and provided at one end with a weight 143 tending to open the valve 141, and at the other end with a notch 145 arranged to receive one end of the lever 146 pivoted centrally upon a vertical axis to the bracket 147, and arranged to normally maintain said valve 141 in closed position. The free end of said lever 146 normally projects laterally from the locomotive and is arranged to be actuated by engagement with either of the stopping blades 77 and 91 of the respective stopping stations, when said blades are projected into the path of said lever as shown at the main stopping stations in Figs. 1 and 2.

The motive power of the locomotive is arranged to be shut off by the air pressure, contemporaneously with the setting of the brakes and to effect such shutting off of the motive power a cylinder 152 is provided, 70 which is supported on the boiler of the locomotive, and is provided with a piston 153 which is connected with a bell crank lever 154, pivoted on the throttle lever 120 which has the hand-grip 155 for its manual operation, said bell crank lever being arranged to actuate said grip to shift the lever bolt 156 to release said bolt from the sector 157.

It will be noted that if the locomotive 5 passes a signal and stopping station when 80 the semaphore 14 is in "danger" position, and the blade 77 is in operative position, the lever 146 will engage said blade and be rocked upon its axis of oscillation to disengage it from the notch 145 of the lever 142, 85 and thereby release said lever, which by means of the weight 143 is shifted to open the valve 141 to effect the actuation of the stopping mechanism carried by the locomotive. If, however, the semaphore 14 and 90 blade 77 are in the "safety" and inoperative position, and the passing of the locomotive into the block protected thereby fails to effect the actuation of the mechanism at the signal station and the main stopping station 95 to shift the semaphore 14 and blade 77 to protect said block, thus occupied, the blade 91 will be engaged by the lever 146 and rocked to release the lever 142 and thereby open the valve 141 to stop the locomotive 100 and permit the operator to either flag a following train or to see that the signals just passed are set to protect the block occupied by his train.

From the foregoing description, it will be 105 obvious that if either the blade 77 of the main stopping station or the blade 91 of the auxiliary stopping station are accidentally or maliciously shifted from their operative position in a direction opposite to their normal direction of movement, the cam groove 83 is effective to uplift the shaft 76 and consequently to withdraw the gears 75 from toothed engagement with the gears 74 so that such movement will not have any effect 110 upon the actuating mechanism, and owing to the inclination of the cam groove 83, said blades 77 and 91 will be immediately returned to their operative position upon being released.

It will be further noted that if the blade 77 be maliciously shifted to an inoperative position after a car or train has passed into the block protected thereby, the electrical connections will be effective to cause the blade 91 to be shifted into operative position 125 so that as will be seen, it will be impossible for a car or train to pass through a block which is not properly protected.

It is not desired to limit this invention to 130

the precise details of construction and arrangement herein set forth, as it is obvious that various modifications may be made therein without departing from the essential features of the invention as defined in the appended claims.

Having thus described my invention, I claim:

1. A railway signal and stopping device comprising a stopping member movable from a predetermined inoperative position to a predetermined operative position, means arranged to shift said member in a given direction from said inoperative position to said operative position, actuating means arranged to shift said stopping member from said operative position to said inoperative position, said stopping member being movable from said operative position in a direction opposite to said first mentioned direction, and means coöperating with said stopping member to disconnect said stopping member from said actuating member when said stopping member is shifted from said operative position in said second mentioned direction.

2. A railway signal and stopping device comprising a stopping member movable from a predetermined inoperative position to a predetermined operative position, means arranged to shift said member in a given direction from said inoperative position to said operative position, actuating means arranged to shift said stopping member from said operative position to said inoperative position, said stopping member being movable from said operative position in a direction opposite to said first mentioned direction, and means coöperating with said stopping member to raise said stopping member and to disconnect said stopping member from said actuating member when said stopping member is shifted from said operative position in said second mentioned direction.

3. A railway signal and stopping device comprising a movable stopping member, means arranged to shift said stopping member from a predetermined inoperative position to a predetermined operative position, actuating means operative to shift said member in a given direction from said operative position to said inoperative position, and a cam and means coöperating therewith to disconnect said member from said actuating means when said member is shifted from said operative position in a direction opposite to said first mentioned direction and to a second inoperative position.

4. A railway signal and stopping device comprising a movable stopping member, means arranged to shift said stopping member from a predetermined inoperative position to a predetermined operative position, actuating means operative to shift said mem-

ber in a given direction from said operative position to said inoperative position, and a cam and means coöperating therewith to disconnect said member from said actuating means when said member is shifted from said operative position in a direction opposite to said first mentioned direction and to a second inoperative position, said cam and means coöperating therewith acting to return said stopping member from said second inoperative position to said first mentioned operative position.

5. A railway signal and stopping device comprising a movable stopping member, a gear arranged to actuate said member, a gear coöperating with said first mentioned gear to shift said member in a given direction from an operative position to an inoperative position, and means coöperating with said stopping member to disconnect said gears when said stopping member is moved from said operative position in a direction opposite to said first mentioned direction.

6. A railway signal and stopping device comprising a stopping member, a gear arranged to actuate said stopping member, a gear arranged to actuate said first mentioned gear to move said member in a given direction from an operative position to an inoperative position, and a cam and means coöperating therewith to disconnect said gears upon the movement of said member from said operative position in a direction opposite to said first mentioned direction, and into a second inoperative position, said cam and means coöperating therewith being operative to return said member from said second inoperative position to said operative position and to cause said gears to return into engagement with each other.

7. A railway signal and stopping device comprising a shaft arranged to rotate through a limited arc about its longitudinal axis and movable longitudinally through a limited distance, a stopping member secured to said shaft and projecting therefrom, a gear fixed on said shaft, a gear engaging said first mentioned gear and operative to swing said stopping member from a given position and in a given direction, and a cam and means coöperating therewith for moving said shaft longitudinally to disengage said gears when said member is swung from said position in a direction opposite to said first mentioned direction.

8. A railway signal and stopping device comprising a shaft arranged to rotate through a limited arc about its longitudinal axis and movable longitudinally through a limited distance, a stopping member secured to said shaft and projecting therefrom, a gear fixed on said shaft, a gear engaging said first mentioned gear, a motor for actuating said second mentioned gear, a clutch between said motor and said second men-

tioned gear, means for automatically connecting said motor to said second mentioned gear through said clutch to rotate said stopping member in a given direction from an operative position to an inoperative position and to disconnect said motor from said second mentioned gear when said member reaches said operative position, means operative to hold said member in said inoperative position and to release said member from said inoperative position, a counter-weight connected to said second mentioned gear for returning said member from said inoperative position to said operative position under the action of gravity when said member is released from said inoperative position, and means including a cam coöperat-

ing with said shaft to move said shaft longitudinally to disengage said gears when said member is rotated from said operative position in a direction opposite to said first mentioned direction and into a second inoperative position, said last mentioned means being operative to return said member to said first mentioned operative position when released from said second inoperative position.

In witness whereof, I have hereunto set my hand this 17th day of August, 1911.

FRANK C. WILLIAMS.
